UNITED STATES PATENT OFFICE.

ROBERT G. CLARK, OF BROOKLYN, NEW YORK, ASSIGNEE TO SAM COHEN MACHINE CORPORATION, OF NEW YORK, N. Y., A CORPORATION OF NEW YORK.

APPARATUS FOR APPLYING STAYS TO BOX CORNERS.

Application filed May 11, 1925. Serial No. 29,379.

This invention relates to apparatus for applying retaining stays or strips to corner joints of boxes made of paper board wherein the stay strip is fed in the form of a web 5 from a supply roll to the stay strip applying means including a fixed anvil upon which the corner of a box formed by the box sides is positioned and the stay strip forcibly applied to said box corner by a presser reciprocable toward and away from the anvil, 10 means being operative with the reciprocation of the presser to sever a fed portion of the web, and means also being provided to longitudinally crease or fold the strip as it 15 is delivered to the strip applying means as well as means to render the stay strip adhesive.

It is an object of the present invention to provide improved means for feeding the 20 stay strip in the form of a continuous strip or web from a supply roll and arranging said feeding means to simultaneously longitudinally fold the web to V shape in cross section and deliver the folded web to means 25 to render one surface of the strip adhesive and to support and fold the strip as it is delivered from the feeding and folding means to the strip applying means.

It is a further object of the invention to 30 provide improved means for rendering the stay strip adhesive as it is delivered by the feeding and folding means to the strip applying means.

In apparatus of this character the strip 35 in its delivery from the supply roll is first folded, then a surface of the strip is rendered adhesive, the strip being fed to said means by means arranged in advance thereof which grips the strip at the adhesively rendered surfaces, and delivered from the feeding means to means which contacts with the adhesively rendered surface of the strip to guide the strip to the strip applying means with the result that the adhesive is removed 40 from portions of the strip and all portions of the strip therefor will not adhere to the corner joints of the box, and it is an object of the invention to provide means to which the folded and adhesively rendered strip is 45 delivered to support and guide the strip to the strip applying means, said strip guiding means being arranged to support the strip without coming in contact with any por-

tion of the adhesively rendered surface of the strip. 55

Other objects and advantages will herein-after appear.

In the drawings accompanying and forming a part of this specification, Figure 1 is 60 a side elevation of a stay strip applying apparatus, with a portion of the supporting standard broken away, and showing an embodiment of my improved strip feeding and folding means applied thereto.

Figure 2 is a cross sectional view, on an 65 enlarged scale, of the strip feeding and folding means, taken on the line 2-2 of Figure 1 looking in the direction of the arrow.

Figure 3 is a side elevation, partly in section, of the actuating means for the strip feeding and folding means and showing the same connected to its operating means. 70

Figure 4 is an end elevation of a guide and support for the adhesively rendered 75 folded strip to direct it to the strip applying means.

Figure 5 is a plan view on an enlarged scale of the stay strip feeding and folding means and showing the means to render the strip adhesive in relation to said feeding and folding means. 80

Figure 6 is a side elevation on an enlarged scale and partly in section of the means for rendering the stay strip adhesive and showing the same in relation to the strip supporting and guiding means; and 85

Figure 7 is a sectional view taken on the line 7-7 of Figure 6 showing the means to render the strip adhesive in relation to the strip supporting and guiding means and in 90 position to render the strip adhesive.

Similar characters of reference designate like parts throughout the different views of the drawings. 95

In the embodiment of the invention illustrated the operative mechanism is mounted upon the framework (designated in a general way at F) supported upon a base B only a portion of which is shown, the framework having an arched portion 8. The stay strip applying means is of the conventional construction and arrangement in apparatus of this character, comprising an anvil 9 to extend forward of and mounted in the framework to have longitudinal adjustment, the upper surface of such anvil being of 100 105

right angle form in cross section and upon which the bent up side flaps of the box blank are engaged with the edges in position to be joined together by a stay strip 10 delivered 5 from a continuous strip or web through an opening in the framework above the anvil. The stay strip positioned relative to the box corner on the anvil is severed and forcibly pressed against the box corner on the 10 anvil by a presser 11 slidably mounted in the forward end of the framework and reciprocatory toward and away from the anvil by a drive shaft 12 journalled in the arched portion of the frame to which the presser 15 is eccentrically connected, as at 13, by a connecting rod 14. Previous to the pressing of the stay strip to the box corner on the anvil the stay strip is severed by a cutter 15 carried by and reciprocable with the presser 20 operating with a cutter 16 fixed in the framework. The drive shaft 12 is rotated from a suitable source of power by a belt 17 passing around a pulley 18 loose on the shaft which is coupled to and uncoupled from the 25 shaft by a clutch 19 operative by a lever 20 pivotally supported upon the framework to which suitable operating means is connected, such as a treadle, not shown.

The stay strip 10 is in the form of an end- 30 less strip or web fed from a supply roller 21 carried by a reel 22 rotatably mounted on a bracket 23. The web preferably had an adhesive applied to one surface to be located at the bottom as the web is fed to the stay 35 strip applying means. The feeding means comprises a pair of rollers 24, 25, the roller 25 being fixed to a shaft 26 journalled in a bracket 27 mounted to have vertical adjustment on a vertically extending portion of an 40 angle bracket 28 by screws 29 engaging a slot in the bracket 27 and threaded into the bracket 28. The bracket 28 is mounted upon the framework to have lateral adjustment by screws 30 engaging in slots in the bracket 45 and threaded into the framework, the real supporting bracket 23 being detachably mounted upon said bracket 28. The roll 24 is fixed to a shaft 31 journalled in a bracket 32 pivotally supported upon the bracket 27, 50 as at 33, (Figures 1 and 5) whereby said roller may be moved into and out of engagement with the roller 25. The rollers are positively driven one from the other by gears 34, 35 fixed to the respective roller carrying shafts 26, 31, enclosed in protecting housings 36 attached to the brackets 27, 32. The roller 24 is yieldingly urged in the direction and held in contact with the roller 25 by a spring 37 (Figure 1) one end of 55 which spring is connected to a lug extending laterally from the housing 36 for gear 35 and the other end of the spring connected to a lever 38 pivotally mounted on the bracket 27. The connection of the spring 60 with said lever is eccentrically to the support

of said lever whereby when the lever is in one position, as shown in Figure 1, the spring will exert a force upon the lever to move a projection of the lever into engagement with a securing boss of the housing 36 70 for gear 34, as shown at 39, and thereby locking the roller 24 in operative relation to the roller 25. To release the roller 24 the lever is actuated to move the projection thereof out of engagement with the gear housing 75 when the one end of the spring may be readily released from the lug extending from the housing for gear 35. The web is guided from the supply roll to the bite of the feeding rollers by threading the same through an eye in a guiding plate 40 (Figure 5) fixed to the bracket 28, the portion of the plate in which the eye is formed being at the extremity and bent upward from the horizontal and the part stamped from the plate to 80 form the eye being bent oppositely and over which the web passes from the supply roll, as clearly shown in Figure 1.

The roller 24 has a peripheral groove of V shape in cross section, and the peripheral portion of the roller 25 is shaped in cross section to conform to said groove and engage therein whereby as the rollers are rotated to feed the web from the supply roll the web or strip will be simultaneously folded longitudinally upon itself to inverted V shape in cross section.

Suitable means are provided for imparting intermittent rotative web feeding movement to the feed rollers alternately with the reciprocation of the presser 11 to feed a predetermined length of the web toward the stay strip applying means. This means is shown as comprising an arm 41 pivotally supported from the arched portion of the frame and oscillated by a roller 42 carried by the arm co-operating with a cam 43 fixed to the drive shaft 12. The free end of the arm has one end of a strap 44 attached thereto the other end of the strap being connected to a drum 45 loosely mounted on the extended end of the feed roller carrying shaft 26 by a U shaped arm 46 of the bracket 27 in which the end of said shaft is journalled, and a wheel 47 having a peripheral groove of V shape in cross section interposed between the drum and the feeding roller 25 and fixed to the feed roller shaft 26. The strap 44 is connected to the drum by folding the end of the strap upon itself and inserting said folded end laterally into a slot, as at 48, in a flange 55 extending laterally from the drum with the strap engaging in an annular recess in said flange. The opposite end of the strip is detachably connected to the arm 41 by looping the end of the strap and engaging said end laterally in a slot in a lug, as at 49, of a coupling member 50, the lug at one end of the slot being recessed for the engagement of the looped strap end, as 130

at 51, to hold the strap from lateral displacement from the slot. The coupling member has an opening to engage said member upon a stud 52 fixed in and extending laterally from the arm 41, and to retain said member against movement by a pull upon the strap in one direction and from displacement from the stud it is arranged with a member 53 to engage about the arm, as clearly shown in Figures 1, 2 and 3. A forward movement of the arm 41 imparted thereto by the cam 43 will impart rotative movement through the strap 44 to the drum in a direction toward the strip applying means, as indicated by the arrow in Figure 3, and reverse movement is imparted to the drum and the cam following roller 42 of arm 41 maintained in operative relation to the cam 43 by a spring 56 coiled about the hub of the drum with one end fixed at 57 to the bracket arm 46 and the opposite end connected to a pin projecting laterally from the drum, as at 58.

Means are provided which is automatically operative to couple the drum to the wheel 47 when the drum is rotated during the forward movement of arm 41 to rotate the wheel and thereby the feed rollers 24, 25 with the drum and operative to uncouple the drum from the wheel with no movement imparted to the wheel when reverse movement is imparted to the drum by the spring 56. For this purpose the drum flange is arranged in overhanging and spaced relation to the periphery of the wheel 47 and carries a pair of diametrically oppositely disposed shoes 60, said shoes being pivotally mounted within the drum flange by engaging a rounded portion thereof laterally into a similarly formed recess in the drum flange, as at 61, the shoes having a part shaped to conform to the V groove in the wheel 47 and to engage in the wheel groove, as at 62, said shoes being urged in a direction to engage in the wheel groove by a spring 63 seated in a recess in the shoes and bearing against the drum flange. The shoes are retained in position in the drum flange by an annular member 64 secured to the drum flange at the side of the shoes opposite to the drum. The end of the shoes are in the form of an arch of a circle as shown and as the drum is rotated through the movement of the arm 41 the shoes through frictional contact with the wall of the groove of wheel 47 will be rocked upon their pivotal supports and caused to be forcibly wedged into frictional contact with the wall of the wheel groove thereby coupling the drum to the wheel 47 and feed rollers 24, 25. As reverse movement is imparted to the drum by the spring 56, the frictional contact of the shoes with the wheel groove will operate to release the shoes therefrom thereby releasing the wheel and disconnecting the feed rollers from the drum.

To feed and fold variable predetermined

lengths of the web adjustable stop means is provided for the arm 41, the adjustment of which stop means is proportional to the adjustment of the anvil 9 and comprises a lever 65 pivotally supported upon the arched portion of the framework, as at 66, one end of the lever being pivotally connected at 67 with the anvil and the opposite end engaging an adjustable stop 67' in the form of a headed set screw threaded into the arm 41, 75 said adjustable stop 67 being provided for effecting further adjustment in the feeding of the web.

The folded web or strip with the gummed surface on the inner or under side thereof is delivered from the feed and folding rollers to means to support and guide the web to the strip applying means. This means comprises a bar 68 fixed to an arm 27^a of the bracket 27 extending forwardly of the feed 85 rollers, the bar 68 being arranged in a horizontal plane with the lower surface substantially in line with the bite between the feed rollers. A member 69 of channel shape in cross section, with one of the flanges 70 of 90 increased width and whereby it is secured to and suspended from the bar 68 with the connecting portion of the flanges of said channel bar in fixed spaced relation to the under surface of the bar 68. By this arrangement 95 the supporting and guiding means as the folded strip is delivered by the feed rollers the outer surface of the fold of the strip will engage with the under side of the bar 68 and the opposite longitudinal edges with the channel bar 69 at the corners formed by the juncture of the connecting portion with the flanges of said member and said means supporting and guiding the strip and maintaining the same in inverted V shape. 100

As stated, one surface of the stay strip or web is gummed, constituting the inner or under surface of the strip when folded, and to render said surface adhesive means are provided to moisten said gummed surface, said means being interposed between the feed rollers and the strip applying means. This means comprises a liquid carrying trough 71 pivotally supported, as at 72, upon the bracket 27 to be adjusted to 110 position below the strip supporting and guiding means and retained in such position by a latch 73 pivotally mounted upon the bracket 27 to swing on an axis transverse to the axis of the trough support. The 115 liquid from the trough is applied to the gummed surface of the web by means engaging in the liquid in the trough and having a part to extend through an opening in the bottom of the channel member guide 69 120 and in engagement with the gummed surface of the strip. This means is shown as comprising a brush to supply the liquid from the trough to the strip to render it 125 adhesive by capillary action. The brush 130

shown is in the nature of a duplex brush, or a pair of brushes 74, 75 mounted in a holder 76 comprising a plate shaped to suitable form and bent upon itself to form the holder for the brushes and having a pair of integral arms 77 whereby the holder is pivotally mounted upon the trough, as at 78. The one brush 74 is arranged so that a part thereof is engaged in the liquid in the trough and the free ends of the bristles pass through the opening in the bottom of the guide member 69 and engage with the strip in the guide. The other brush 75 is arranged in contiguous relation to the brush 74 with the free ends of the bristles immersed in the liquid in the trough, as clearly shown in Figure 6, whereby should the liquid level in the trough below the liquid will be transmitted by capillary action from the brush 75 to the brush 74. To regulate the liquid applied to the strip the delivery of liquid by the brush 74 by capillary action is regulated by squeezing the bristles of said brush together to a more or less degree. For this purpose there is provided a roller 79 extending transversely of the brush bristles in opposed relation to a fixed wall of the brush holder and eccentrically mounted in the holder. To rotate said roller it is provided with a handle 80. It will be obvious that by rotating said eccentrically supported roller the bristles of the brush will be squeezed together to a more or less extent, and the tighter they are squeezed together the less will be the capillary action of the brush and the application of moisture to the strip. The brush 74, as stated, engages in the strip through an opening in the bottom of the guide member 69, as shown in Figures 6 and 7. This opening is formed by transversely slitting the bottom of said guide member at predetermined points, and then slitting the portion of the bottom between said transverse slits longitudinally of and midway between the sides of said guide member. These slitted portions are then bent downwardly and laterally, as shown at 81, and the portions of the bottom of the guide member at opposite ends of said portions 81 are bent or deflected slightly as at 82. By this arrangement any surplus liquid will be drained back into the trough.

The brush 74 contacts with the gummed surface of the strip in the guide, and the ends of the bristles of the brush are so shaped that they will engage with the entire surface of the strip, as shown in Figure 7. To maintain the brush forcibly though yieldingly in contact with the strip a spring 83 is provided connected at one end to the trough and brush holder, as at 84, said connection being such that when the brush is in contact with the strip in the guide the longitudinal axis of the spring will be above a line extending through the supporting

arms of the brush holder and its pivotal support, and the spring will function to maintain the brush holder in its raised position with the brush in contact with the strip in the guide. The upward movement of the brush is limited by the ends of the holder arms 77 coming into engagement with the trough, as at 85. When the apparatus is not in use to prevent any gum which might adhere to the bristles from hardening thereon the brush holder is adjusted into the trough so that the free ends of the bristles will be immersed in the liquid therein, as shown in dotted lines in Figure 6, the holder being retained in such position by the spring 83. By the arrangement of pivotally mounting the trough it may be swung to position away from below the strip guiding means for replenishing the liquid, cleaning or otherwise. The contact of the brush with the strip firmly holds it in its advanced position.

To further guide the strip after it has been rendered adhesive the upper guide member or bar 68 is extended forwardly of the lower guide member 69 toward the strip applying means, as clearly shown in Figure 1. At the extremity of the bar a guide and support 86 for the lower marginal edges of the strip is provided the lower wall of which inclines from the front to the rear to facilitate the passing of the strip therethrough, and a plate 87 to engage the upper surface of the strip, the V shape edge being arranged as a cutting edge whereby the strip extending forward of the same may be severed by exerting an upward pull thereon to remove a portion of the strip the gummed surface of which has not been rendered adhesive, since should the apparatus be stopped for any length of time with the stay strip therein the gummed surface of the strip forwardly of the means for rendering the strip adhesive becomes dry and consequently would not adhere to a box corner on the anvil. Should the apparatus be stopped a sufficient length of time for the gummed surface previously rendered adhesive to become dry the apparatus is operated until the gummed surface of the strip delivered from the guiding means 86, 87 is adhesive when the strip is severed at said guide.

By the arrangement of guiding means described it will be obvious the strip is supported and guided at all times with no part of the guiding means in contact with the adhesive surface and a possibility of removing part of the adhesive. Furthermore, there is no strain whatever upon the strip from the feeding to the strip applying means with the result there is no possibility of the strip being broken. Also the threading of the strip to the feeding and guiding means is greatly facilitated since all that is

required is to thread the strip through the eye of the plate 40 to guide the same to the feed and folding rollers when the strip is guided to the strip applying means through 5 the feeding movement of the feed rollers.

While I have illustrated and described one embodiment of the invention it is obvious that various modifications may be made in construction and arrangements of 10 parts and that portions of the invention may be used without others and come within the scope of the invention.

Having thus described my invention I claim:

15 1. In apparatus for the purpose specified, stay strip applying means including a fixed anvil and a reciprocatory pressing member to co-operate with the anvil, means operative alternately with the pressing member 20 to intermittently feed a stay strip toward the strip applying means and simultaneously longitudinally crease the same, and means arranged intermediate the feeding means and the applying means to render said strip 25 adhesive.

2. In apparatus for the purpose specified, stay strip applying means including an anvil and a reciprocatory pressing member to co-operate with the anvil, means to intermittently feed a stay strip from a supply 30 roll in a direction toward the stay applying means and simultaneously fold the same to V shape in cross section, means to which the stay strip is delivered from said feeding and folding means to guide the strip at the edges 35 and fold to the applying means, and means arranged intermediate the feeding means and the applying means and relative to said guiding means to render the stay strip adhesive.

40 3. In apparatus for the purpose specified, stay strip applying means including an anvil and a reciprocatory pressing member to co-operate with the anvil, means to intermittently feed a web having a gummed surface toward the applying means and simultaneously longitudinally fold the same to V shape in cross section with the gummed surface on the inner side thereof, means arranged intermediate the feeding means and applying means to which the folded web is delivered from the feeding means to support and guide the web at the ungummed surface, and means arranged relative to said guiding means to moisten the gummed surface 45 of the web.

4. In apparatus for the purpose specified, stay strip applying means including an anvil and a reciprocatory pressing member to co-operate with the anvil, means to intermittently feed a web having a gummed surface toward the applying means and simultaneously longitudinally fold the same to V shape in cross section with the gummed surface 50 on the inner side thereof, a liquid car-

rying trough intermediate the feeding means and applying means, and means having a part to engage in the liquid in the trough and a part to engage with the gummed surface of the web to moisten said 70 gummed surface through capillary action as the web is fed.

5. In apparatus for the purpose specified, stay strip applying means including an anvil and a reciprocatory pressing member to 75 co-operate with the anvil, means to intermittently feed a web having a gummed surface toward the applying means and simultaneously longitudinally fold the same to V shape in cross section with the gummed surface 80 on the inner side thereof, a liquid carrying trough intermediate the feeding means and applying means, means arranged in superposed relation to said trough to guide and maintain the web in its folded 85 condition, and means to engage in the trough and with the gummed surface of the web to moisten the gummed surface of the web during the feeding thereof.

6. In apparatus for the purpose specified, stay strip applying means including an anvil and a reciprocatory pressing member to co-operate with the anvil, means to intermittently feed a web having a gummed surface toward the applying means and simultaneously longitudinally fold the same to 90 V shape in cross section with the gummed surface on the inner side thereof, a liquid carrying trough intermediate the feeding means and applying means, means arranged 95 in superposed relation to said trough to guide and maintain the web in its folded condition, and a brush pivotally supported by the trough to partly engage therein and the free ends of the bristles to engage the 100 gummed surface of the web in the guiding means to moisten the same.

7. In apparatus for the purpose specified in accordance with claim 6 wherein means is provided to yieldingly urge the brush into 110 engagement with the web in the guide.

8. In apparatus for the purpose specified in accordance with claim 6 wherein a brush is adjustably carried in the trough and adapted to be adjusted to position to engage the web in the guiding means and out of engagement with the web and to engage in the trough, and means to yieldingly urge the brush in a direction toward the web when in engagement therewith and said means 115 being adapted to retain the brush in position in the trough when adjusted to position out of engagement with the web.

9. In apparatus for the purpose specified, stay strip applying means including an anvil and a reciprocatory pressing member to co-operate with the anvil, means to intermittently feed a web having a gummed surface toward the applying means and simultaneously longitudinally fold the same to V 125 shape in cross section with the gummed surface on the inner side thereof, a liquid car-

shape in cross section with the gummed surface on the inner side thereof, a liquid carrying trough intermediate the feeding means and applying means, means arranged in superposed relation to said trough to guide and maintain the web in its folded condition, and a brush pivotally supported by the trough, said brush being arranged with bristles the free ends of which engage in the trough and with bristles the free ends of which engage with the gummed surface of the web in the guiding means to moisten the same.

10. In apparatus for the purpose specified, stay strip applying means including an anvil and a reciprocatory pressing member to co-operate with the anvil, means to intermittently feed a web having a gummed surface toward the applying means and simultaneously longitudinally fold the same to V shape in cross section with the gummed surface on the inner side thereof, a liquid carrying trough intermediate the feeding means and applying means, means arranged in superposed relation to said trough to guide and maintain the web in its folded condition, a brush, a carrier for said brush pivotally mounted on the trough to partly engage the brush in the trough and position the free ends of the bristles in engagement with the gummed surface of the web to moisten the web by capillary action, and said carrier being arranged with adjustable clamping means for the brush to increase or decrease the capillary action thereof.

11. In apparatus for the purpose specified, in accordance with claim 6, wherein a brush is adjustably carried by the trough and adapted to be adjusted to position to engage partly in the trough and with the gummed surface of the web in the guiding means, and to be adjusted out of engagement with the web and to engage wholly in the trough, and a spring operative to yieldingly urge the brush in a direction toward the web when in engagement therewith and to retain the brush in the trough when adjusted to position therein and out of contact with the web.

12. In apparatus for the purpose specified, stay strip applying means including an anvil and a reciprocatory pressing member to co-operate with the anvil, means to intermittently feed a web having a gummed surface toward the applying means and simultaneously longitudinally fold the same to V shape in cross section with the gummed surface on the inner side thereof, a liquid carrying trough intermediate the feeding means and applying means, means arranged in superposed relation to said trough to guide and maintain the web in its folded condition, a brush pivotally carried by the trough to partly engage therein and the free ends of the bristles to engage an opening in the guiding means and the gummed surface of the web, and the opening in the guiding

means being arranged to direct surplus moisture from the web to the trough.

13. In apparatus for the purpose specified, stay strip applying means including an anvil and a reciprocatory pressing member to co-operate with the anvil, means to intermittently feed a web having a gummed surface toward the applying means and simultaneously longitudinally fold the same to V shape in cross section with the gummed surface on the inner side thereof, a liquid carrying trough intermediate the feeding means and applying means, means arranged in superposed relation to said trough to guide and maintain the web in its folded condition, a brush, a carrier for said brush pivotally mounted on the trough to partly engage the brush in the trough and position the free ends of the bristles in engagement with the gummed surface of the web to moisten the web by capillary action, and said carrier being arranged with adjustable clamping means for the brush to increase or decrease the capillary action thereof.

14. In apparatus for the purpose specified, stay strip applying means including an anvil and a reciprocatory pressing member to co-operate with the anvil, means to intermittently feed a web having a gummed surface toward the applying means and simultaneously longitudinally fold the same to V shape in cross section with the gummed surface on the inner side thereof, means interposed between the feeding means and applying means to guide and maintain the web in its folded condition, a pivotally supported liquid carrying trough adapted to be adjusted to position below the guiding means, and a brush adjustably mounted on the trough and adapted to partly engage therein and with the free ends engaging with the gummed surface of the web in the guiding means to moisten said surface of the web.

15. In apparatus for the purpose specified, stay strip applying means including a fixed anvil and a presser reciprocatory toward and away from the anvil, means operative alternative with the presser to feed a predetermined length of a strip toward the stay strip applying means and simultaneously longitudinally fold the same to V shape, means interposed between the strip applying means and feeding means operative during the feeding of the strip to render the undersurface thereof adhesive, and means to which the strip is delivered from the feeding and folding means to support and guide the strip to the strip applying means without contacting with the adhesive rendered surface of the strip.

16. In apparatus in accordance with claim 15 wherein the stay strip supporting and guiding means comprises a fixed bar for

engagement of the bend of the strip, and a channel member extending parallel and in spaced relation to the bar for engagement of the edge portions of the strip.

- 5 17. In apparatus for the purpose specified, stay strip applying means including a fixed anvil and a presser reciprocatory toward and away from the anvil, a pair of rollers to feed and simultaneously longitudinally fold the stay strip, means to intermittently rotate said rollers to feed a predetermined length of the strip, means to render one surface of the folded strip adhesive during the feeding thereof, and means 10 to which the fed and folded strip is delivered from the rollers to support and guide the strip to the strip applying means without contacting with the adhesively rendered surface of the strip.
- 15 18. In apparatus for the purpose specified in accordance with claim 17 in which the means to impart feeding movement to the feed and folding rollers comprises a drum rotatably supported coaxially of one 20 of the feed rollers and normally urged in one direction, means operative alternately with the reciprocation of the presser to impart reverse rotative movement to said drum, and means to couple said drum to the 25 one feed roller during the latter movement of the drum.

- 30 19. In apparatus for the purpose specified, stay strip applying means including a fixed anvil and a presser reciprocatory toward and away from the anvil, a drive shaft to which the presser is eccentrically connected to reciprocate the presser from the rotation of the shaft, a pair of rollers one 35 roller having a V-shaped peripheral groove and the other roller having the periphery shaped to conform to and engage in the groove of the first roller, said rollers being operative to feed and simultaneously longitudinally fold said strip to V shape and 40 deliver the folded strip to the strip applying means, and means operative from the drive shaft to intermittently rotate said rollers alternately with the reciprocation of the presser to feed a predetermined length 45 of folded strip toward the strip applying means.

- 50 20. In apparatus for the purpose specified in accordance with claim 19 in which the means to impart feeding movement to the rollers comprises a drum rotatably supported coaxially of one of the rollers, a spring to normally urge said drum in one direction, a cam on the drive shaft, a pivotally supported arm arranged with a cam 55 follower to oscillate said arm by the cam from the rotation of the shaft, a strap to operatively connect the arm with the drum to impart movement to the drum in a direction reverse to that in which it is moved by 60 its spring as the arm is moved in one direction.

engagement of the bend of the strip, and a channel member extending parallel and in spaced relation to the bar for engagement of the edge portions of the strip.

70 21. In strip feeding means for stay strip applying apparatus, a pair of rollers one of said rollers having a peripheral V groove and the periphery of the other roller shaped to conform to and engage in the peripheral groove of the first roller to feed and simultaneously longitudinally fold the strip to V shape in cross section, means to rotate said rollers in one direction comprising a drum 75 rotatably supported coaxially of one of the rollers, a wheel arranged concentrically of the drum rotatable with the one roller, and means to couple the drum to said wheel and the feed rollers when rotated in one direction and release the drum therefrom when rotated in reverse direction.

80 22. In strip feeding means for stay strip applying apparatus in accordance with claim 21 wherein the rollers are fixed on rotatable shafts and the drum is loose on the shaft of one roller and the wheel is fixed to said shaft within and concentrically of the drum.

85 23. In strip feeding means for stay strip applying apparatus in accordance with claim 21, wherein the rollers are fixed on rotatable shafts, the drum is loose on one of said shafts and the wheel is fixed to said shaft within and concentrically of the drum, of an overriding clutch interposed between the drum 90 and wheel operative to couple the drum with the wheel and rollers when the drum is rotated in one direction and release the drum therefrom when rotated in reverse direction.

95 24. In strip feeding means for stay strip applying apparatus in accordance with claim 21, wherein the rollers are fixed on rotatable shafts and one shaft driven from the other shaft by a gear on one shaft meshing with a gear on the other shaft, and means to rotate the rollers in one direction comprising 100 a drum loose on one of the roller shafts, a wheel fixed to said shaft arranged within the drum, and over-riding clutch mechanism operative to couple the drum to said wheel and the rollers when the drum is rotated in one direction and release the drum therefrom 105 when rotated in reverse direction.

110 25. In strip feeding means for stay strip applying apparatus in accordance with claim 21, wherein the rollers are fixed upon rotatable shafts and the one shaft positively driven from the other shaft, a drum loose on one of the roller shafts, a wheel arranged concentrically of the drum fixed to said shaft having a peripheral V-groove, said 115 drum being urged in one direction by a spring, and means for coupling the drum to the wheel and rollers comprising spring influenced shoes pivotally carried by the drum 120 adapted to frictionally engage the wall of 125 the drum.

the peripheral groove of the wheel when the drum is rotated in one direction against the action of the spring and said shoes moved out of frictional engagement with the wheel groove and release the drum from the wheel when the drum is rotated in reverse direction by the spring.

26. In strip feeding means for strip applying apparatus in accordance with claim 10 21, in which the one roller is positively driven from the other roller and one roller is pivotally supported and yieldingly urged into engagement with the other roller.

27. In apparatus for the purpose specified 15 in accordance with claim 19 in which the means to impart feeding movement to the rollers comprises a drum rotatably supported coaxially of one of the rollers, a spring to normally urge said drum in one direction, 20 a cam on the drive shaft, a pivotally supported arm arranged with a cam follower to oscillate said arm by the cam from the rotation of the shaft, a strap having one end connected to the arm by a coupling member 25 arranged with a slot for engagement of a looped end of the strap and having a perforation to engage the member upon a stud in the arm, and said member arranged with a part to engage about the arm to hold it 30 against pivotal movement on and displacement from the stud, and means to operatively connect the drum to the one roller during said latter movement of the drum, said

means being automatically released from the roller when the drum is rotated by its spring. 35

28. In strip feeding means for stay strip applying apparatus, means to feed and simultaneously longitudinally fold the strip upon itself to V shape in cross section, means to which the strip is delivered from the feeding and folding means to render a surface of the strip adhesive, and means for supporting, guiding and maintaining the strip in V shape as it is delivered from the feeding and folding means, during the period it is 45 being rendered adhesive and delivered from said adhesive rendering means without contacting with the adhesive surface of the strip.

29. In stay strip applying apparatus, strip feeding and folding means, and means to 50 render the strip adhesive to which the strip is delivered from and by the feeding means.

30. In stay strip applying apparatus, strip feeding and folding means, means to render the strip adhesive to which the strip is delivered from and by the feeding means, and means to support and guide the strip as it is delivered to the adhesive rendering means and delivered from said latter means without 55 contacting with the adhesively rendered surface of the strip. 60

Signed at New York city, in the county of New York and State of New York this 4th day of May, 1925.

ROBERT G. CLARK.
